(57) **CLAIM**

The ornamental design for a surface configuration of a portion of a dashboard for a vehicle, as shown and described.

DESCRIPTION

This application is related to the following co-pending application, of the inventor, filed on even date herewith: Application Ser. No. 29/225,371, entitled “surface configuration of a dashboard for a vehicle”.

FIG. 1 is a top perspective view of a surface configuration of a portion of a dashboard for a vehicle according to my novel design;

FIG. 2 is a front view of the surface configuration of a portion of a dashboard for a vehicle according to my novel design;

FIG. 3 is a top view of the surface configuration of a portion of a dashboard for a vehicle according to my novel design; FIG. 4 is a right perspective view of the surface configuration of a portion of a dashboard for a vehicle according to my novel design; and,

FIG. 5 is a reduced perspective view of the surface configuration of a portion of a dashboard for a vehicle according to my novel design, showing the placement on the dashboard. The broken line showing of environment is for illustrative purpose only and forms no part of the claimed design.

1 Claim, 3 Drawing Sheets

FIG. 5
